UNITED STATES PATENT OFFICE.

ISAAC JONES, OF KNOXVILLE, IOWA.

DITCHING-PLOW.

SPECIFICATION forming part of Letters Patent No. 470,491, dated March 8, 1892.

Application filed July 16, 1891. Serial No. 399,742. (No model.)

To all whom it may concern:

Be it known that I, ISAAC JONES, a citizen of the United States, residing at Knoxville, in the county of Marion and State of Iowa, have 5 invented certain new and useful Improvements in Ditching-Plows; and I do declare the following to be a full, clear, and exact description of the invention, such as will enable others skilled in the art to which it appertains 10 to make and use the same, reference being had to the accompanying drawings, and to letters of reference marked thereon, which form a part of this specification.

This invention relates to an improvement 15 in ditching-plows; and it consists in the certain peculiar features of construction and arrangement of parts more fully hereinafter described, and definitely pointed out in the claim.

20 The object of my invention is to form a plow for cutting ditches adapted especially for draining-tiles, which will be simple in its construction, embodying the fewest number of movable parts, and which can be readily 25 transported to and from the place of operation. This object I accomplish by the construction illustrated in the accompanying drawings, wherein like letters of reference indicate like parts in the several views, and in 30 which—

Figure 1 is a perspective view. Fig. 2 is a top plan view, and Fig. 3 is a side elevation with the parts arranged for transportation.

In the drawings, A represents the plow-beam 35 supported on the front and rear axles B and B', upon which suitable wheels are placed, the axle B' being pivoted to the beam on its upper side and the axle B rigidly secured on the upper side of the front end of the beam. To 40 retain the axle B' in a rigid position, I secure two straps C and C', pivoted on the axle on each side of the beam and having their inner ends adjustably secured to the beam at the front of the axle, so that the axle will be held 45 in a rigid position at right angles to the beam when the plow is in operation.

When it is desired to transport the plow, the forward ends of the straps are loosened and removed from the beam and swung over in the rear of the axle, at which point they are attached to a suitable tongue D, so that

the front axle may be moved to turn the machine.

In securing the axle B' to the beam I interpose a block E and insert a pivot-pin e 55 directly through the axle and block. This block elevates the wheels so that the lower portions thereof are on the same plane as the lower parts of the front wheels, thereby holding the plow in a perfectly horizontal position. F is a brace on the upper side of the axle B', extending forward and secured to the beam. On the rear end of the beam, to one side thereof, is rigidly secured an inclined mold-board G, having a flaring upper end inclining to one side and a tapering lower end terminating in a shoe G², placed at an incline of less angle than the mold-board. This mold-board has a backing of wood G³, which forms a support for the same. The side of the mold-board next to the standard is carried up vertically to form a plate H, which has its upper end rigidly secured to the beam. This plate is at right angles to the mold-board and acts as a retaining-wall for the earth that passes 65 up over the mold-board, thereby conducting the same to one side of the ditch. 70

I is a parallel beam located on the side of the forward portion of the beam proper, having interposed between a block I' at its rear end and clevis-block I² at its forward end, to which the power is attached. On the side of this supplemental beam I is a metallic bar J, extending back to point beyond the shoe. The rear end of this bar is provided with a 80 vertical colter extending down to and attached to the lower end of the mold-board or point thereof, having a cutting front edge. 85

K is an inclined colter and brace secured to the rear end of the supplemental beam, 90 crossing the vertical colter on the outside and secured to the lower end of the mold-board. On the opposite side of the beam is an inclined colter and brace L, secured to the beam between the same and the supplemental beam 95 and rigidly connected at its lower end to the point. In the rear of this colter is a vertically-disposed cutting blade or colter secured to the beam and to the mold-board, respectively. These colters are inclined inwardly toward the lateral center of the plow, and the front portions of the inclined colters 100

serve to sever the soil in advance of the plow or point, while the knives or colters serve to trim the walls of the ditch dug. The rear end of the bar J is bent outwardly, so that the upper end of the vertical colter attached thereto will engage the soil in the rear of the forward colter.

By the above-described construction it will be seen that as the power is applied to the forward end of the plow the same will be drawn into the ground, severing the earth and carrying it up the mold-board off to one side of the ditch cut and in rear of the wheels. The power that I preferably use is a windlass or capstan; but any other desired means may be employed.

By placing the axles of the machine on the top of the beam and rigidly securing the other parts to the beam it is evident that all that is necessary is to turn the plow over, throwing the mold-board up. The braces are then

detached and the tongue secured in place, when the device is ready for transportation.

Having thus described my invention, what I claim as new, and desire to secure by Letters Patent, is—

In a ditching-plow, the combination, with the main beam having a mold-board secured to one side thereof and extending down at an angle, colters extending from the beam to the mold-board, axles mounted on top of the beam, wheels on the axles, and adjustable braces on one axle for holding it in its adjusted position and to which a tongue is attached when the plow is reversed for transportation, substantially as described.

In testimony whereof I affix my signature in presence of two witnesses.

ISAAC JONES.
